UNITED STATES PATENT OFFICE.

ROBERT DÈUSER, OF BERLIN-CHARLOTTENBURG, GERMANY, ASSIGNOR TO WESTING-HOUSE ELECTRIC & MANUFACTURING COMPANY, OF NEW YORK, N. Y., A CORPORATION.

DEVICE FOR AUTOMATICALLY CUTTING OUT DEFECTIVE SECTIONS IN ELECTRIC DISTRIBUTION NETWORKS.

Application filed February 27, 1925. Serial No. 12,051.

To all whom it may concern:

Be it known that I, ROBERT DÈUSER, a citizen of the German Empire, residing at Berlin-Charlottenburg, Germany, have invented certain new and useful Improvements in Devices for Automatically Cutting Out Defective Sections in Electric-Distribution Networks, of which the following is a specification.

10 My invention relates to improvements in devices for automatically disconnecting defective sections in electric distribution networks.

15 The networks of electric plants are subdivided into individual sections in order that in case of a breakdown the defective section only may be disconnected. In a known protective system commonly designated the split-conductor system the selection and disconnection of the defective sections is attained by controlling in each phase the current distribution in the main and the auxiliary conductor connected in parallel with it at the beginning and the end by special devices (differential transformers). When a fault appears in the section the current ratio in the main and the auxiliary conductor changes and the control devices effect the instantaneous disconnection of the section. By means of coupling transformers a control voltage is generated between the main and the auxiliary conductor.

20 It is desirable that the disconnection of the defective section should take place as quickly as possible so that the operation of the sound portions of the network is not disturbed. It follows that sound parts of the network must under no circumstances be disconnected by excess currents which originate from breakdowns in the defective section. The fault protecting device must thus not respond even in the case of large excess currents.

25 The object of my invention is to provide a device by means of which a split-conductor system is made insensitive against the appearance of excess currents. My invention is based upon the recognition that the system does not respond to excess currents when the ratio of the currents in the main and auxiliary conductor remains unchanged at any load and no phase displacement appears between the two conductors. My in-

vention consists in keeping at a constant ratio the currents in the main and auxiliary 55 conductor and a phase displacement of zero between these currents.

In the drawing affixed to this specification and forming part thereof various embodiments of my invention are illustrated 60 by way of example.

Fig. 1 is illustrative of the prior art.

Fig. 2 shows the invention as applied to a system such as shown in Fig. 1.

Figs. 3 and 4 show modifications.

Referring to Fig. 1, 11 and 12 are the main and the auxiliary conductor of the section which is adapted to be disconnected at both its ends by means of the switches 13 and 14. 15 and 16 are coupling transformers by the aid of which a voltage is maintained between the conductors 11 and 12. 17 and 18 are differential transformers which by means of the windings 19 and 20 transmit voltage to the relays or tripping 75 devices 21 and 22 only when owing to a defect in the section the normal current distribution in the two conductors is changed. When the relays 21 and 22 respond, the latches 23 and 24 of the switches 13 and 14 80 are disengaged and the switches disconnect the defective section from the network.

In such an arrangement, voltages which originate from the ohmic resistances of the section, and from magnetic fields flowing in 85 iron which are not free from saturation tend to disturb the normal ratio of the currents in the conductors 11 and 12. Furthermore voltages which originate from magnetic fields flowing entirely or mainly in air and 90 consequently from magnetic stray fluxes which form around the windings of the transformers and differential transformers, and from magnetic fields which close around the main and auxiliary conductor must be 95 taken into consideration.

As the partial voltages of these three groups have different phase relations to the load current, the equalization of the voltages to zero is according to my invention carried 100 out separately for each group. Assuming always that the current ratio between main and auxiliary conductor is chosen correctly so that the differential transformers do not respond and assuming that the phase displacement of the load currents in the main 105

and auxiliary conductor is equal to zero, the sum of all the ohmic voltage drops, the sum of all the voltages which originate from the magnetic fluxes in the iron and the sum of all the voltages which originate from the power fluxes mainly flowing in the air must be equal to zero in the section.

The equalization of the ohmic voltage drops in the circuit 18, 11, 14, 12, 13 may 10 be effected by connecting in said circuit an additional adjustable resistance or rheostat. If the auxiliary conductor 12 has a smaller cross-sectional area than the main conductor 11 and thus carries a small current in comparison with the total current, the additional resistance is preferably placed in the auxiliary conductor and distributed over the beginning and the end of said conductor. Such adjustable additional resistances 25, 20 26 are illustrated in Fig. 2. In order to enable the adjustable additional resistance to be placed in the auxiliary conductor and thereby to keep the energy losses as low as possible, the ratio between the currents in 25 the main and auxiliary conductor may be chosen somewhat higher than corresponds with the ratio of the cross-sectional areas of the section conductors. Of course all other elements of the system must be suitably proportioned in accordance with the chosen 30 current ratio and in particular all windings must be dimensioned correspondingly.

Voltages which originate from magnetic fields flowing in iron and which are not free 35 from saturation occur in the coupling transformers 15 and 16 even when the lines show no defect. If the sum of the voltages of the two transformers is zero for any load, the magnetic inductions of the coupling transformers are equal for any load, or the two 40 transformers possess the same magnetizing curve which condition cannot be realized in actual practice.

Magnetic fields flowing in air exist as 45 stray fluxes around all windings traversed by the main and the auxiliary current or in the coupling transformers 15 and 16, the differential transformers 17 and 18 and also around the main and auxiliary conductors 50 of the section. Cables are ordinarily employed as conductors. If in a cable the auxiliary conductor is located concentrically to the main conductor, a magnetic field exists which is interlinked with main and auxiliary conductor and also a field which is only 55 interlinked with the main conductor. It is well known that this causes a current displacement in the main conductor and a phase displacement of the currents of the two conductors. Generally the sum of the voltages 60 which originate from these magnetic fluxes will not be zero under the current ratio chosen. According to my invention the adjustment of the sum of the voltages to zero 65 is brought about by an additional power

flux which mainly flows in air. To attain this end two transformers 27 and 28 are connected to the main and the auxiliary conductors, as shown in Fig. 2 which have a core member containing an air gap. Since 70 the iron circuits are not closed but have an adjustable air gap, the magnetic field receives the properties of an air field. The windings of the magnet system traversed by the main and auxiliary current oppose each other. In the present case the ampere windings originating from the main current must, however, preponderate.

In order to maintain a perfect balance in 75 the protective system upon the occurrence of excess currents, it is still necessary to eliminate the influence of the capacity between main and auxiliary conductors. Since a potential exists between main and auxiliary 80 conductors capacity currents flow from the transformers 15 and 16 towards the main conductor 11, then together across the dielectric to the auxiliary conductor 12 and hence 85 separately again back to the coupling transformers. These capacity currents are superimposed upon the load currents and alter the current ratio in the main and auxiliary conductor. The effect of these disturbing currents is eliminated if additional ampere 90 turns 29, 30 (Figure 2) are allowed to act 95 upon the differential transformers which ampere turns balance the ampere turns produced by the disturbing capacity currents at any load.

In the arrangement shown in Fig. 2 the 100 windings 29, 30 of the differential transformers are connected with the control voltage generated by the coupling transformers in series relation with the condensers 31 and 32. The number and the direction of the 105 turns of the additional winding and the size of the condensers are so determined that the effect of the disturbing capacity currents is eliminated.

In Fig. 3 another modification of my improved system is illustrated. A special winding 33 of the coupling transformer 15 and also a corresponding winding of the transformer 16 at the other end of the line are connected with the windings 35 of the 115 differential transformers traversed by the auxiliary current in series relation with condensers 34.

The equalization of the sum of all the voltages in the section to zero may also be 120 applied to other designs of a split-conductor protection system. Such an arrangement is illustrated in Fig. 4 in which coupling transformers and differential transformers are combined to a single magnet system.

The coupling transformer is provided with a middle leg 36 which at the top and at the bottom is connected with points of the transformer iron between which no magnetic potential difference exists in normal service. 125 130

If, however, in case of a defect the magnetic fluxes in the iron change a potential difference appears at the connecting points of the central leg. An electromotive force is induced in the winding 37, thereby energizing the trip coil 19 so that the switch is opened. Upon the central leg 36 there is also arranged the coil 38 which is connected with the voltage between the main and the auxiliary conductors in series relation with a condenser 39 corresponding to the coil 29 of the Fig. 2. In this arrangement also the result is attained that the sum of all the voltages in the circuit of the section is equal to zero at any load.

What I claim as my invention is:

1. An electrical distribution system comprising a split-conductor section having main and auxiliary conductors arranged in parallel relation, means arranged at each end of said section for disconnecting the section upon the occurrence of a disturbance

of the normal ratio of currents traversing said conductors and means including inductive and condensive devices connected to the section for compensating for the unbalancing of currents resulting from unbalanced inductance and capacity in the said conductors.

2. An electrical distribution system comprising a split-conductor section having main and auxiliary conductors arranged in parallel relation, means arranged at each end of said section for disconnecting the section upon the occurrence of a disturbance of the normal ratio of currents traversing said conductors and means including a non-saturating inductance device and a condenser connected between said conductors for compensating for the unbalancing of currents resulting from unbalanced inductance and capacity in the said conductors.

In testimony whereof I affix my signature.

ROBERT DÈUSER.
